UNITED STATES PATENT OFFICE.

CHARLES FREDERICK HARRISON, OF LEVENS HULME, MANCHESTER, ENGLAND.

AUTOMATIC SAFETY SHUTTER AND MOTOR CONTROL FOR PICTURE-PROJECTING MACHINES.

Application filed October 13, 1925, Serial No. 62,281, and in Great Britain April 30, 1925.

This invention relates to cinematograph or picture projecting machines, and has for its object to provide means whereby in the event of an abnormal variation in the tension of the film, say by breaking or becoming unduly slack or tight, the light of the lantern will be automatically intercepted, and the motor by which the machine is operated stopped, thereby reducing the risk 10 of fire to a minimum, as well as preventing further damage to the film.

According to the invention, use is made of a shutter adapted to move across the path of the light, or be held out of such path, 15 means being provided to normally retain the shutter in the retracted position. Use is also made of an electro-magnet for releasing said shutter-retaining means, and of at least one switch in the magnet circuit for 20 completing such circuit, the switch being acted upon by the film to close the magnet circuit when the tension of the film varies from the normal, as aforesaid. On said shutter may be a further switch contacting 25 with a stationary two-part bar alongside the shutter, the switch and one part of the bar being in the circuit of the motor which drives the machine, so that, with the opening and closing of the shutter, the motor is 30 started and stopped.

When there is no film passing through the machine, the switch in the magnet-circuit (or one of the switches when more than one) 35 normally completes the circuit, but when a film is properly threaded through the machine, said switch is held by the film so as to break the magnet circuit. In this way the machine is prevented from running unless a film is first and properly inserted, thereby 40 affording additional safety in the use of the machine.

The invention will be fully described with the aid of the accompanying drawings, wherein:—

45 Fig. 1 illustrates a general arrangement of cinematograph machine, with one example of the invention applied thereto, parts of the film reel boxes being shown broken away.

50 Fig. 2 illustrates a diagram of the electrical connections of the improved safety mechanism.

Fig. 3 illustrates to a larger scale, a front view of the shutter and magnet control and of the frame or casing supporting same, the

cover of the frame or casing being shown removed.

Fig. 4 illustrates a side view, and

Fig. 5 a plan of a portion of the circuit control mechanism.

In Fig. 1, *a* is the lantern, *b* the projector, and *c¹*, *c²* the film reel boxes of the ordinary picture projecting machine. *d* is the frame or casing part of the improved safety appliances attached to the lantern on the side 60 next the projector by means say of studs *d¹* and plates *d²*. In the plates *d²* and in the back or rear wall of the casing *d* and also in the cover of same, is formed a rectangular aperture, through which the light from the 70 lantern normally passes. *e* is a shutter within the casing *d* sliding in vertical guides *f*. Such shutter is normally held in a raised position above the aperture by means of the bolt or plunger *g* sliding in 75 the horizontal guides *h*, the normal position of the plunger *g* being determined by a spring *i* and lever *j*.

k is an electro-magnet, and *l* the "keeper" of such magnet, said "keeper," at its 80 lower end, adjustably engaging the upper end of the lever *j*, and under the influence of the regulable spring *m*, normally being held clear of the magnet poles, as shown. The spring *i* also serves to maintain contact 85 between the "keeper" *l* and the lever *j*. On the shutter *e* but insulated therefrom is a switch *n* in rubbing contact with a bar *o* on but insulated from the frame *d*. Such bar is in circuit with the electric motor used 90 for driving the machine. At its lower end the bar *o* is divided to provide an insulated gap, whereby on the shutter *e* being lowered and the switch *n* passing the gap, the motor circuit will be broken and the motor 95 stopped, and similarly, on the shutter being raised and the switch passing from the lower to the upper bar, the motor will be restarted.

Adjacent to the usual upper feed roller 100 *p* are two pivoted metal plates or blades *r¹*, *r²* normally resting against pins *s*, *s*. The pivots of the blades and the pins *s*, *s* are conveniently supported by the side wall of a housing or hood *t*, this latter being made 105 of metal and lined with fibre or like insulating material *t¹*. To the hood *t* are applied pairs of terminals *u*, *u* of the electric circuit of the magnet *k*, against the points of which one or both of the blades *r¹*, *r²* 110

may impinge when raised and thereby complete the circuit of the magnet k .

To one edge of the insulating material or hood is secured a pivoted guide roller carrier v yieldingly held in the position shown in Fig. 4 by a spring v^1 and screw v^2 so that the film in passing from the roller p is guided into the hood t by the roller v^3 , the film following the usual loop form before entering the gate, b^2 , see Fig. 4. On the open side of the hood is a stay rod t^2 for preventing the film leaving the hood sideways.

Below the gate b^2 and between the lower feed roller w and the lower film reel box c^2 is a pivoted lever x , on one arm of which is mounted a roller x^1 . The other arm of the lever, in conjunction with terminals x^2 , constitutes a switch for completing or breaking the circuit of the magnet k . The lever x is mounted on the axis of the usual bottom guide roller. On its way from the bottom feed roller w to the lower film reel box c^2 the film q passes below the roller x^1 and over the guide roller y .

With the film intact and running smoothly at its normal tension, the plates r^1 , r^2 lie clear of the terminals u , u and the lever x is held clear of the terminals x^2 .

The film almost invariably breaks in the gate, but may also break at any point above or below the gate. Assuming the film to break in the gate, the broken end is held and the film ceases to pass through the gate, but by reason of the continued delivery of the film from the upper reel box c^1 the loop of the film rapidly assumes large proportions, or in other words, "balloons" within the hood t , and contacting with one or both of the plates r^1 , r^2 moves it, or them, into contact with the respective terminals u , u thereby completing the circuit of the magnet k . Immediately the magnet is energized, the "keeper" l operates the lever j to release the safety shutter e , which instantly falls and closes the aperture in the frame d .

Simultaneously with the film ballooning and operating the switch plates r^1 , r^2 the switch lever x , loses the support of the film, and contacts with the terminals x^2 . This also happens in the event of the film breaking at points other than in the gate, say above the loop, or between the gate, and the lower reel box.

The switches will operate in the same manner in the event of a film not breaking, but merely slackening.

Although undue tightening of the film is of rare occurrence, a further switch and terminals may be provided which will complete the magnet circuit when the film tightens to an unusual extent. Such additional switch will be arranged within the loop of the film, and may consist of a plate z^6 slidable in slotted supports and normally

held out of contact with terminals z^6 by light springs z^7 see Fig. 4.

As the shutter falls and is approaching its lowest point, the switch arm n passes the gap in the bar o and breaks the circuit of the motor used for driving the machine. Immediately after the shutter is released by the lever j , it may break the magnet circuit and thus prevent waste of current or undue exhaustion of the battery. For such purpose the shutter may be furnished with a switch arm z and the casing d with terminals z^1 with which the arm z engages when the shutter is fully raised to complete the magnet circuit, the circuit being broken on the arm leaving the terminals with the falling of the shutter.

To re-open the shutter after repairing or replacing the film, a handle z^2 is provided, pivotally mounted in the frame d . In placing or inserting a film, the operator first threads the film between the rollers p and p^1 and below roller v^3 ; he then passes same through the gate b^2 , then between the feed roller w and rollers w^1 , w^2 , then below roller x^1 and over roller y and into the reel box c^2 . Unless the film is passed below the roller x^1 the switch arm of the lever x will contact with the terminals x^2 and prevent the restarting of the machine. In this way a safeguard is provided against inserting a repaired film or a new film without also at the same time resetting the safety devices.

To allow the operator to see to repair or insert a film, the fall of the shutter e may be used to switch on a light and for such purpose the shutter may be fitted along its lower edge with a pivoted switch bar e^1 designed to engage a pair of terminals e^2 fitted to a piece of insulating material carried by the casing d , said terminals being in circuit with an electric lamp z^8 . On the shutter being raised, the circuit of the lamp is broken and the light extinguished. A switch z^4 may serve to switch on the light, independently of the machine.

With the safety shutter e additional to the ordinary shutter, this latter will be free to be operated in the usual way without interference from the safety shutter.

What I claim is:—

1. In picture projecting machines embodying a lantern, a projector, a gate, upper and lower film feeding and guiding rollers, film reel boxes and an electric motor for driving the machine; in combination, a series of electric switches operated by the ballooning, tightening, slackening, or breaking of the film, terminals for said switches, means for supporting some of said switches and terminals near the upper film feeding roller, another of said electric switches and terminals therefor being supported near to the lower film feeding roller, all the terminals being connected with an electro-magnet and

those switches near the upper feeding roller normally lying clear of their terminals and the switch near the lower guiding roller normally lying in contact with its terminals. 5 such last named switch being in the form of a lever and being axially mounted on the axis of the lower guiding roller of the machine, and said lever having on one arm a further guiding roller, under which latter, after passing over the 65 lower guiding roller, the film passes and when correctly tensioned, holds the switch clear of its terminals, a switch arm on the shutter, an interrupted bar on the casing in which the shutter slides, but insulated 70 therefrom, over which the switch arm may travel as the shutter moves up or down, said bar being in circuit with the electric motor for driving the machine and on the shutter falling and the switch arm passing from 75 one part of the bar to the other, the circuit of the motor being broken and the motor stopped, as set forth.

2. In picture projecting machines and in safety appliances therefor as claimed in 80 claim one, a pair of pivoted metal blades or switches, adjacent the upper film feed roller, a hood for supporting the axes of said blades, or switches, terminals carried by said hood in circuit with the electro-magnet 85 and with which the blades or switches are adapted to contact but which normally lie clear of said terminals, the arrangement being such that the film on breaking and/or unduly slackening or ballooning presses 90 against one or other or both of the blades or switches and causes them to contact with the terminals and complete the circuit of the magnet, substantially as herein set forth.

3. In picture projecting machines and in 95 safety appliances therefor as claimed in claim one, a pair of pivoted metal blades or switches, adjacent the upper film feed roller, a hood for supporting the axes of said blades, or switches, terminals carried by said hood in circuit with the electro-magnet 100 and with which the blades or switches are adapted to contact but which normally lie clear of said terminals, the arrangement being such that the film on breaking and/or unduly slackening or ballooning presses 105 against one or other or both of the blades or switches and causes them to contact with the terminals and complete the circuit of the magnet, substantially as herein set forth.

4. In picture projecting machines and in 110 safety appliances therefor, a series of electric switches collectively operated by either the ballooning, tightening, slackening or breaking of the film, an electro-magnet common to all said switches and electrically connected therewith and a shutter controlled by such electro-magnet for shutting off the light when the film balloons, tightens, slackens or breaks, one of said switches comprising a lever on the axis of the bottom guide 115 roller or sprocket wheel of the machine, a pair of stationary terminals near to one arm of the lever, said terminals being connected with the electro-magnet, and said lever having a roller or further sprocket wheel on the arm furthest from the terminals, whereby 120 on a film being placed in the machine and passed over one roller or wheel and below the other, the tension of the film serves to hold the lever clear of the terminals, while immediately the film breaks or slackens unduly, the lever makes contact with the terminals and completes the magnet circuit, the said circuit remaining completed until the lever is again held clear of the terminals by 125 a film, substantially as herein set forth.

In testimony whereof I have signed my name to this specification.

C. F. HARRISON.
